UNITED STATES PATENT OFFICE

FRANK BOUCHER, OF DETROIT, MICHIGAN

GARAGE DOOR OPENER

Application filed December 18, 1930. Serial No. 503,322.

This invention aims to provide means whereby the doors of a garage or other building may be opened and closed by an automobile, means being provided whereby one door 5 can be opened and closed by a person on the ground, either inside the garage, or outside of it.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope 23 of what is claimed, without departing from the spirit of the invention.

In the accompanying drawings:

Figure 1 shows, in vertical longitudinal section, a garage in which the device forming the subject matter of this application has been mounted;

Figure 2 is a horizontal section on the line 2—2 of Figure 1;

Figure 3 is a detail enlarged from Figure 20 1, some parts being in section;

Figure 4 is a horizontal sectional view of the rider, attendant parts appearing in plan, the view being taken on the line 4—4 of Figure 3;

Figure 5 is a bottom plan of one of the door-operating bars, parts being broken away, and the parts being in section;

Figure 6 is a vertical section on the line 6—6 of Figure 3;

Figure 7 is a side elevation of the carriage;

Figure 8 is a vertical section of the carriage;

Figure 9 is a plan of the movable tracks and attendant parts;

Figure 10 is a horizontal section of the structure depicted in Figure 9;

Figure 11 is a section on the line 11—11 of Figure 9;

Figure 12 is a section on the line 12—12 of Figure 9;

Figure 13 is a section on the line 13—13 of Figure 9;

Figure 14 is a section on the line 14—14 of Figure 9;

Figure 15 is a section on the line 15—15 of Figure 7;

Figure 16 is a section on the line 16—16 of Figure 7;

Figure 17 is a section on the line 17—17 of Figure 7;

Figure 18 is a section on the line 18—18 of Figure 7;

Figure 19 is a section on the line 19—19 of Figure 7;

Figure 20 is a section on the line 20—20 of Figure 3;

Figure 21 is a section on the line 21—21 of Figure 3;

Figure 22 is a vertical section through one of the doors, and showing the mechanism which makes possible the hand-actuation of the said door, at the will of an operator;

Figure 23 is a section on the line 23—23 of Figure 22.

In Figures 1, 2 and 3, the numeral 1 designates a garage or other building, having doors 2 and 3 which are hinged to swing horizontally.

On the floor of the garage 1 are mounted loop-shaped end guides 4 (Figures 9 and 11), one of these guides being located within the garage, and the other of the said guides being located without the garage, as Figure 1 will show. Referring to Figures 11 and 12, it can be seen that the end guides 4 rest on base plates 6. Lower spacers 7 are mounted on the bottom portions of the end guides 4, and upper spacers 5 are secured to the top portions of the end guides. The outer or remote ends of arched casings 8 rest on the lower spacers 7. Securing elements 9 pass downwardly through the said ends of the casings 8, through the lower spacers 7, through the bottom portions of the end guides 4, and through the base plates 6, into the floor of the garage 1, as shown in Figures 11 and 12.

Spacers 10 are interposed between the adjacent or inner ends of the casings 8 and the floor of the garage 1 (Figure 12). Securing elements 11 connect the adjacent or inner ends 100 of the casings 8.

of the casings 8 and the spacers 10, with the floor of the garage 1.

Beneath the crown of each casing 8 is located a vertical shaft 12 having its lower end 5 reduced and received in a socket 14 (Figure 12) which is mounted in the floor of the garage 1. The upper end of each shaft 12 is secured at 15 to the crown of the casing 8. Pinions 16 (Figures 10 and 12) are journaled 10 on the shafts 12, beneath the casings 8, and the hubs 17 of the pinions rest on the upper ends of the sockets 14. The casings 8 not only serve as guards for the pinions 16, but they function as lifting members for certain 15 moving parts, and as carriage stops, an observation which will be more clearly understood when the reading of this specification has progressed considerably beyond the present point.

20 Comparing Figures 9 and 13, intermediate guides 18 are secured to the garage floor, as is also a center guide 19, which is shown in cross section in Figure 14.

The parts 4, 18 and 19 are called guides, because 25 slides 20 and 21 have parallel, right line movement in them. The relation of the slides 20 and 21 to the garage 1 is shown in Figures 1 and 2: Figure 9 and Figure 10 show them on a larger scale, and Figures 11, 13 and 30 14 make it evident that the slides are channel members. The slides 20 and 21 are held apart transversely, for right line sliding movement, by the spacers 5 and 7 of Figures 11 and 12, and by the spacer 10. The vertical walls of 35 the slides 20 and 21 have racks 22 wherewith the pinions 16 mesh, reference being had especially to the left hand end of Figure 10.

Oppositely-projecting, horizontally-operating cam blocks 23 and 24 (Figure 9) are 40 secured (Figure 13) to the bottoms of the intermediate guides 18, the cam blocks 23 being disposed at the inner edge of the slide 20, and the cam block 24 being disposed at the inner edge of the slide 21. In Figure 10, 45 there is shown a horizontal projection 25 on the slide 20, the said projection being located a little behind the back end of the cam block 23. On the slide 20, there is a similar projection 26, disposed slightly to the rear of the forward end of the cam block 23. The slide 21 has a projection 27 which is placed a short 50 distance in front of the rear end of the cam block 24, and the slide 21 has a projection 28 located slightly in advance of the forward end 55 of the cam block 24.

A flexible element 29 (Figures 9, 2 and 1) is connected to the rear end of the slide 21. A flexible element 30 is connected to the rear end of the slide 20. The flexible elements 29 and 60 30 pass upwardly over pulleys 31 secured to the rear end of the garage 1, near to the floor, and from the pulleys 31, the flexible elements pass upwardly and forwardly over pulleys 32 which are mounted on the rear wall of the 65 garage 1, near to the roof of the garage. The

flexible element 30 is carried over a pulley 33 (Figures 1 and 3), and is extended backwardly, the pulley 33 being mounted on a post 34 that extends downwardly from the roof of the garage. The post 34 may be sustained by 70 horizontal braces 35 (Figures 1 and 2) connected at their forward ends to the roof of the garage, or elsewhere.

Behind the post 34 are two rigid vertical depending hangers 36 (Figures 1 and 3), and the forward hanger abuts against the post 34. The hangers 36 support parallel horizontal tracks 37, on which is mounted, for horizontal straight line movement, a rider 38, the rider being U-shaped in side elevation (Figure 3), and U-shaped in end elevation (Figure 6). Grooved wheels 39 are journaled on the rider 38 and move between the tracks 37. Depending from the intermediate portion of the rider 38 is a stud bolt 40 80 (Figure 3). The inner ends of the pull springs 41 are connected to the stud bolt 40, and therefore to the rider 38. The outer end of one of the pull springs 41 is connected to the flexible element 29, and the outer end of the other pull spring is connected to the flexible element 30, behind the pulley 33.

Referring to Figure 2, it is evident that the device comprises forwardly extended, diverging connections 42 and 43, in the form 95 of bars. The forward end of the connection 43 is pivoted at 44 to a block 45 on the inner surface of the door 3. At their rear ends (Figure 3) the bars 42 and 43 have flattened extensions 46 that are overlapped on 100 each other and pivoted to the rider 38, by means of the depending stud bolt 40.

The connection between the bar 42 and the door 2 is of a somewhat more complicated 105 make-up than the simple pivot 44 (Figure 2) that joins the bar 43 to the door 3, the construction now to be explained being desirable in order that a person may open the door 2 by hand.

Figure 22 shows, in connection with Figure 1, that there is a horizontal upper bracket 47 and a horizontal lower bracket 48 on the inner surface of the door 2, there being a hole 49 in the door 2, below the bracket 48. A bushing 50 (Figure 23) is held by a pin 51 110 in the bracket 47. In the bushing 50 and in the lower bracket 48, a vertical latch rod 52 is mounted for straight-line movement. The latch rod 52 has a shoulder 53, and a compression spring 54 is interposed between the shoulder and the lower bracket 48. At its lower end, the latch rod 52 is provided with a transverse handle 55 which extends inwardly with respect to the lower bracket 48, and outwardly through the hole 49, so that the handle can be grasped either from the inside of the door 2, or from the outside of the door, to pull the latch 52 down. On the upper end (Figure 22) of the bushing 50 is pivoted a link 56, mounted to slide (Figure 120

3) in the guides 57 located (Figure 5) on the lower edge of the bar 42. The rear end of the link 56 is received between guard plates 58 (Figures 3 and 20) secured to the bar or door connection 42. The upper end 59 (Figures 3 and 22) of the latch 52 is received in a keeper 60 which is mounted in the forward portion of the bar 42. The forward end of the bar 42 is beveled, and carries a metal wear plate 61, leading back to the keeper 60.

A carriage 62 is mounted to move on the slides 21 and 20, and in this connection, note Figures 7, 8, 15 and 16 of the drawings.

The carriage 62 is provided at its ends with axles 63, whereon are journaled vertical wheels 64 that roll along the lower flanges of the slides 21 and 20. The carriage 62 is provided near to one end and at its upper edge, and near to the opposite end and at its lower edge, with horizontal rollers 65 which are adapted to cooperate with the vertical walls of the slides 20 and 21, as shown in Figure 15.

As disclosed in Figures 7 and 17, pickup members 67 and 68 are mounted to slide horizontally in the carriage 62, crosswise of the carriage. The working end of the pick-up 68 (Figure 17) cooperates with the projections 25 and 26 (Figure 10) of the slide 20, and the working end of the pick-up 67 cooperates with the projections 27 and 28 of the slide 21. A U-shaped carrier 69 (Figure 17) is slideable on the pick-up 68 and has in its lower portion, a depending projection 70, in the form of a roller. On the pick-up 68 there is an abutment 71. A compression spring 72 is interposed between the abutment 71 and one side of the carriage 62. A compression spring 73 is interposed between the opposite side of the carriage 62 and the adjacent end of the carrier 69. The pick-up member 67 is correspondingly arranged, saving for the fact that its spring 72 acts to the left instead of to the right as in Figure 17, the spring 73 acting to the right instead of to the left as in Figure 17, an observation which will be understood readily when it is recalled that the working ends of the pick-up members 67 and 68 are on opposite sides of the carriage 62. The numeral 74 in Figures 7 and 8 designates a projection or roller, corresponding to the roller 70 of Figure 17.

An upstanding operating member or lever 75 is pivoted at 76 (Figures 18 and 8), at its lower end, on the intermediate portion of the carriage 62, to swing parallel to the line of advance of the carriage. The lever 75 has a vertically adjustable extension 77 held in place by a cotter pin 78 (Figure 19) adapted to be mounted in any one of a plurality of holes 79 (Figure 8) in the lever 75.

Oppositely extended braces 80 and 81 are pivoted at 91 to the lever 75, the brace 80 having a downwardly curved end 82, and the brace 81 having a downwardly curved end

83. The brace 81 has a depending shoulder 84 adapted to cooperate with a keeper 85 on the carriage 62. The brace 80 has a depending shoulder 86 adapted to cooperate with a keeper 87 on the carriage 62. The braces 80 and 81 are drawn downwardly by pull springs 88 connected to the braces and to the carriage 62. When the lever 75 is tilted out of the vertical, it is restored to vertical position by the action of pull springs 89 having their inner ends connected to the lever, their outer ends being anchored on the carriage 62.

Suppose that the doors 2 and 3 of the garage 1 are closed, the carriage 62 being in the condition of Figure 7, aside from the fact that the curved end 83 of the brace 81 has ridden up on the casing 8 (Figure 12) that is disposed adjacent to the end guide 4 that is located outside of the garage, as shown at the right end of Figures 1 and 2 of the drawings. The carriage 62, at this time, is outside the garage 1 and has come to a stop against the left hand end of the casing 8 (Figure 12).

The pick-up member 67 of Figure 7, corresponding to the pick-up member 68 of Figure 17, has been advanced by its spring 72, until the working end of the pick-up member 67 is between the projections 27 and 28 (Figure 10) of the slide 21, and is engaged with the edge of the projection 28, the projection 27 at this time being considerably to the right of the cam block 24, and not in the position shown in Figure 10.

The front axle of the automobile is marked by the numeral 100 in Figure 1, although the axle, in that figure, is in a position quite different from that which it will assume at the step in the operation now under discussion. The front axle 100, being without the garage 1, engages the extension 77 of the lever 75, on the carriage 62, the lever being held against swinging to the left in Figure 7, because the shoulder 86 on the brace 80 is engaged with the keeper 87 on the carriage 62. The auto moves the carriage 62 to the left in Figure 1, and the slide 21 of Figure 10 is moved to the left also, as soon as the pick-up 67 on the carriage 62 engages the right hand edge of the projection 27 on the slide 21. As the slide 21 moves to the left in Figure 10, the slide 20 is moved to the right, because the slides are operatively connected through the instrumentality of the pinions 16 and the racks 22.

As the slide 21 moves to the left, the flexible element 29, which is connected to the slide 21, is slackened away, and the rider 38 of Figure 3 is permitted to move to the right in Figure 3, along the tracks 37. The rider 38 moves to the right, as aforesaid, under the action of the flexible element 30, which is pulled upon when the slide 20, to which it is connected, moves to the right.

As the rider 38 moves to the right, and

assumes the position of Figure 3, the connections 42 and 43 are advanced, to the position of Figure 2, the connection 42 opening the door 2, and the connection 43 opening 5 the door 3.

As the carriage 62 moves to the left in Figure 10, its depending roller 74 (Figure 7) rides on the cam block 24 of Figure 10. (Here note Figure 17 for the construction of 10 the roller 74, that roller corresponding to roller 70 of the pick-up 68.) When the roller 74 of the pick-up 67 moves to the left in Figure 10, over the cam block 24, the carrier 69 cooperates with the abutment 71, compressing 15 the spring 72, and sliding the pick-up 67 from between the projections 27 and 28 of Figure 10, the roller 74 moving over to the left of the projection 27 in Figure 10. The carriage 62 now is freed from the slide 21, the slide 21 20 no longer moves with the carriage 62, as the carriage 62 is propelled into the garage, along with the auto. As the carriage 62 is moved into the garage by the auto, the wheels 64 of the carriage roll along the lower flanges of 25 the slides 20 and 21, as indicated in Figures 15 and 16.

When the auto is in the garage 1, the projection or roller 70 (Figure 17) on the pick-up 68 rides over the cam 23 of Figure 10, 30 and this moves the pick-up 68 to the left in Figure 17, and when the roller 70 is clear of the cam 23, the spring 72 reacts and moves the pick-up 68 to the right in Figure 17, so that the working end of the pick-up 68 is between the projection 25 and 26 of the slide 20 35 in Figure 10, and the working end of the pick-up 68 engages the right hand edge of the projection 25. The slide 20 is carried to the left in Figure 10, and the slide 21 is carried 40 to the right, because the slides are connected, through the racks 22 and the pinions 16. When the slide 20 moves to the left, the flexible element 30 (Figure 1) is slackened off, and the flexible element 29, which is connected 45 to the slide 21, is pulled upon, as the slide 21 moves to the right. This operation moves the rider 38 to the left in Figure 1, and the connections 42 and 43 of Figure 2 close the doors 2 and 3 behind the auto, which 50 is now in the garage.

The axle 100 of the auto is to the right of the lever 75-77 of the carriage 62, as shown in Figure 1, but, ultimately, the rounded end 55 82 (Figure 7) of the brace 80 rides up on the casing 8 that is adjacent to the end guide 4 shown within the garage, at the left end of Figure 1, Figure 12 being noted at this point, so that the construction under discussion can be readily recalled. As the rounded end 50 82 of the brace 80 rides on the casing 8, the brace is raised so that its shoulder 86 is above the keeper 87 of Figure 7, the lever 75-77 60 tilting to the left, so as to enable the axle 100 of the auto (Figure 1) to move to the left 65 of the lever 75-77 on the carriage 62. As

soon as this occurs, the right hand spring 89 in Figure 7 reacts, erects the lever 75-77, and restores the parts 84-85 and 86-87 to the position of Figure 7, the lever 75-77 being held rigidly in place, so as to move 70 the carriage 62 to the right in Figure 1, as soon as the auto is started out of the garage.

When the auto moves out of the garage, the operation hereinbefore described is reversed, the doors first being opened, to let 75 the auto out of the garage, and then being closed behind the auto, after it is out of the garage. Since what takes place when the auto leaves the garage is a mere reversal of what takes place when the auto enters the 80 garage, there is no occasion for commenting at length upon this step, it being necessary, merely, to state that when the auto moves out of the garage, the projections 26 and 28 (Figure 10), instead of the projections 25 85 and 27, are the parts that do the work.

Attention is directed to the fact that the slides 20 and 21 not only form part of the means for opening and closing the doors 2 and 3, but also afford a track on which the 90 carriage 62 moves. The members 20 and 21 therefore exercise a double function, and make it unnecessary for the builder to supply a special track for the carriage 62 to travel upon. 95

The springs 41 of Figure 1 take up sudden shocks and prevent the doors 2 and 3 from being slammed open or slammed shut. The adjustment afforded at 78-79-75-76 in Figure 8 effects a change in the length 100 of the carriage lever, so that it will cooperate with auto axles of different heights.

Refer to Figures 3, 1 and 22. If the operator wishes to open the door 2 by hand, he pulls down the latch rod 52 by means of 105 the handle 55, so that the upper end 59 of the latch rod is not engaged in the keeper 60 of the door-operating bar 42. The door 2 then can be swung open by hand, the link 56 moving to the right in Figure 2, in the 110 guides 57. When the operator shuts the door 2, the link 56 slides back in the guides 57, the end 59 of the latch rod 52 rides under the wear-plate 61 on the end of the bar 42, and the end 59 of the latch rod engages 115 again in the keeper 60 of the bar 42, under the upward thrust of the spring 54 of Figure 22.

Having thus described the invention, what is claimed is:

1. In a device of the class described, a door mounted for movement between open and closed positions, a pair of slides mounted for relative right line reciprocation in parallel relation, means for connecting one slide to the door to open the door, means for connecting the other slide to the door to close the door, a first mechanism for connecting the slides operatively together, to cause them to move in opposite directions, when either slide 120 125 130

- is actuated, a carriage movable longitudinally of the slides and having a vehicle-engaging part, and a second mechanism actuated by the movement of the carriage longitudinally of the slides for coupling the carriage first to one slide and then to the other slide.
2. A device of the class described, constructed as set forth in claim 1, and further characterized by the fact that said first mechanism comprises racks on the slides, and a pinion supported for rotation and meshing with the slides.
3. A device of the class described, constructed as set forth in claim 1, and further characterized by the fact that the slides serve as a track on which the carriage moves and is supported.
4. A device of the class described, constructed as set forth in claim 1, and further characterized by the fact that the means for connecting the slides to the door comprises a rider, means for mounting the rider for reciprocation, a connection between the rider and the door, flexible elements connected, respectively, to the slides, and connected to the rider, and means for supporting the flexible elements, so that they operate as a loop.
5. A device of the class described, constructed as set forth in claim 1, and further characterized by the fact that said vehicle-engaging part is a lever pivotally mounted on the carriage, oppositely extended braces pivoted to the lever and engaged with the carriage to hold the lever upright, means engageable with the braces to disengage them one at a time from the carriage and to permit the lever to tilt as the carriage approaches the limits of its travel, and yieldable means for erecting the lever and restoring the braces to engagement with the carriage, when the carriage is moved away from said means for disengaging the braces from the carriage.
6. A device of the class described, constructed as set forth in claim 1, and further characterized by the fact that said second mechanism embodies projections on the slides, pick-up members mounted for reciprocation in the carriage, spring means cooperating with the pick-ups to advance them for engagement with the projections, and fixed cams wherewith portions of the pick-ups engage, as the carriage is reciprocated, to retract the pick-ups against the action of said spring means.
7. A device of the class described, constructed as set forth in claim 1, and further characterized by the fact that the means for connecting the slides to the door embodies a releasable mechanism under the control of an operator, whereby the operator may open the door independently of the slides.

In testimony that I claim the foregoing as my own, I have hereto affixed my signature.

FRANK BOUCHER.
